UNITED STATES PATENT OFFICE.

KAHN MURAKAMI, OF BERKELEY, CALIFORNIA.

HAT.

1,249,454.

Specification of Letters Patent. Patented Dec. 11, 1917.

Application filed October 11, 1915. Serial No. 55,270.

To all whom it may concern:

Be it known that I, KAHN MURAKAMI, a subject of the Emperor of Japan, residing at Berkeley, in the county of Alameda and State of California, have invented certain new and useful Improvements in Hats, of which the following is a specification.

My invention relates to hats, and more particularly to the manner of constructing hats and has for its primary object the provision of a cheap and durable material from which a hat may be formed.

Another object of the invention is to provide a hat built up of a plurality of strips of paper or the like twisted and braided to provide strands which may be wound and interlaced to build up a hat.

With the above and other objects in view my invention resides preferably in the construction, combination, and arrangement of parts as hereinafter set forth in the specification as illustrated in the accompanying drawings, in which—

Figure 1 is a plan view of the hat in process of forming, employing my improved strands;

Fig. 2 is a plan view of one of the strips from which the twisted strands are formed;

Fig. 3 is a similar view of one of the strips partly rolled or twisted;

Fig. 4 is a perspective view of the hat in process of formation showing my improved strands in use in another form, and

Fig. 5 is a sectional view of the arrangements of strands shown in Fig. 4.

Similar reference characters designate similar parts throughout the various views of the drawings.

More specifically, my invention embodies a strip of paper or the like designated 1, said strip being rolled or twisted as indicated at 2 in Fig. 3 to provide a strand of pliable material easily woven or braided to afford the strand from which my hat is built up.

In Fig. 1, I have shown one manner in which the strip 1 may be employed to form a hat. In this form, a plurality of twisted strips are braided as indicated at 3 to provide a single strand designated 4. The strand 4, as shown to advantage in Fig. 1, is spirally wound to form, in this instance, the crown of the hat, the hat being indicated in dotted lines and designated 5. When the crown has been built up from the strand 4 the convolution of said strand may

be sewed or otherwise structurally connected so as to form a firm, yet pliable body.

In Fig. 4, I have illustrated another application of my invention. The strand 1 is flattened as shown to advantage in Fig. 5 and interwoven as indicated at 6 in Figs. 4 and 5. This will form the brim of the hat and it will be seen that a cheap and durable structure for the brim of the hat is thereby provided.

It is to be understood that while I have described the strands 1 as being of paper, these strands may be of any strong and durable material and in some instances I may utilize straw or ratan, braiding said strands in the same manner in which the paper strips are braided. Furthermore, by forming the crown of a single strand of material which is composed of strips of paper twisted and braided, and then spirally wound, an exceedingly pliable structure is afforded and also, one which will stand rough usage, due to the reinforced nature of the material from which it is formed. The rim by being constructed from strips of twisted material which is wound and interwoven, presents a brim of sufficient stiffness to maintain the same in proper form and prevent sagging thereof; also, by forming the crown of coil material, a great amount of flexibility is imparted thereto, thus, permitting the same to be adjusted to the head of the wearer.

From the above description taken in connection with the accompanying drawings, it is thought that a clear and comprehensive understanding of the construction, use and application of my invention as well as its advantages may be readily gathered and while I have shown and described the same as embodying a specific structure, I reserve the right to make changes therein which do not depart from the spirit and scope of the invention as claimed.

What is claimed is:

1. As an article of manufacture, a hat comprising a crown formed from spirally wound flexible strips of material whereby said crown may yield slightly to conform in shape to the wearer's head, and a brim formed upon said crown composed of interwoven strips of material, thereby forming a stiff brim which will hold its shape irrespective of the yielding of said crown.

2. As an article of manufacture, a hat comprising a crown formed from spirally

wound flexible strips of material, whereby said crown may yield slightly to accommodate different sized and shaped heads, and a brim formed upon said crown composed of 5 flat interwoven strips, a plurality of the last mentioned strips extending at right angles to the remaining strips of the last mentioned strips, thereby presenting a stiff brim which will hold its shape irrespective of the yielding of said crown, and the outer faces of 10

said last mentioned strips extending in substantially even planes, thereby causing said brim to present even surfaces.

In testimony whereof I affix my signature in presence of two witnesses.

KAHN MURAKAMI.
